CLAIM

The ornamental design for a microphone, as shown and described.

DESCRIPTION

FIG. 1 is a rear and left side isometric view of a microphone showing our new design;

FIG. 2 is a front and right side isometric view thereof;

FIG. 3 is a top pln view thereof;

FIG. 4 is a rear elevational view thereof;

FIG. 5 is a front elevational view thereof; and,

FIG. 6 is a right side elevational view thereof, the left side being a mirror image.

The broken line showing of the microphone apertures, cable attachment and base are for illustrative purpose only and form no part of the claimed design.
